UNITED STATES PATENT OFFICE.

GEORGE HUNTER ROBINSON, OF LONDON, ENGLAND, ASSIGNOR TO THE BELDAM PACKING AND RUBBER COMPANY, LIMITED, OF LONDON, ENGLAND.

PACKING FOR PISTON RODS AND THE LIKE.

Application filed March 11, 1926, Serial No. 94,012, and in Great Britain November 18, 1924.

This invention relates to flexible metallic or semi-metallic packing for piston rods and the like of the kind comprising a bar of double wedge shape in section adapted to be folded together to form a V in order to complete its formation as a packing. Under modern conditions of increasing high temperatures and pressures the working face of the packing must be as hard as possible in order to resist both wear and fusion but with the methods hitherto adopted in connection with packing of the kind to which the invention relates it is impossible to secure the required degree of hardness consistent with flexibility necessary to enable the packing to be bent.

The object of the present invention is to overcome the above difficulty and the invention consists in metallic or semi-metallic packing comprising a bar of double wedge shape in section adapted to be folded together to form a V, the double wedge parts being of suitable metal to form the working face while the junction between such parts is formed of a suitable ductile metal embodied in the bar and enabling the parts of the bar to be bent and folded together.

The invention also consists in other details and arrangements hereinafter described or indicated.

The accompanying drawings illustrate two modes of carrying out the invention.

Figure 1 is a sectional elevation of a mould with a ductile metal strip therein.

Figure 2 is a section of the composite metallic packing formed by the apparatus of Figure 1.

Figure 3 is a plan of the packing with an asbestos or like backing secured thereto.

Figure 4 is a plan showing a part of the metallic packing bent round to engage a piston or other rod.

Figure 5 is a view of the packing shown in Figure 2 bent into a V shape.

Figure 6 is a view of a modified form of packing, and

Figure 7 shows the asbestos or like backing.

In carrying my invention into effect in one convenient manner, as, for example, in its application to a metallic packing of the kind comprising a bar of white metal or other anti-friction or bearing metal of approximately double wedge-shaped section provided upon each side with saw-cuts or

gaps placed in staggered relation to one another and such that the bar may be subsequently bent up from the sides to form an approximate V shape, I employ a mould or die comprising two parts, a, b, (Figure 1) 60 one of which, a, is shaped to give the double wedge-shaped section, and within the mould or die I place a strip c of soft ductile metal of the required length and size, the strip extending for the full length of the die or 65 mould which corresponds to the length of the bar to be formed. The central part of the strip is gripped tightly between the two mould parts at the centre and the strip projects or extends for a predetermined distance into each side of the mould, the extending or projecting part being serrated or having a cleaned and roughened surface or being otherwise formed or treated to secure the necessary adhesion between such strip 70 and the hard anti-friction metal which is subsequently run into the mould to form the double wedge parts d which subsequently 75 form the wearing face of the packing.

The anti-friction metal may be run into the mould at a temperature which is somewhat higher than the melting point of the flexible or ductile strip so that when the two metals come into contact there will be a slight surface flow of the ductile metal 80 allowing the two to amalgamate at their surfaces.

Alternatively, the strip may be tinned to secure proper adhesion, or it may be formed with holes therein so that the anti-friction 90 metal will key itself to the strip by lodgment within said holes, or in general any suitable method may be adopted to secure the intimate contact and proper adhesion between the two metals. 95

In this way I am enabled to produce a bar, the wearing face of which may be of any desired hardness while the median portion of the bar will be of sufficient flexibility to enable the bar to be bent up from the 100 sides to an approximate V formation.

In an alternative arrangement shown in Figure 6, I may provide a plurality of thin strips e superposed upon one another so that their central portions are tightly gripped 105 between the mould parts while the portions projecting into the hollow mould may be separated from one another or spread substantially fan-wise so that when the anti-friction metal is run into the mould it will 110

flow freely between the separated parts of the sheets and thus make for itself a secure anchorage, but will not flow between the abutting central portions which are gripped between the mould parts.

In slotting the bar transversely to secure the necessary flexibility for bending round a piston rod or the like, as shown in Figure 4, the slots *f* are preferably cut right through the hard part of the bar and extend a short distance into the soft flexible back part, as shown in Figure 3, the slots being in staggered relation to one another in known manner and after having been bent to a required diameter, the ring may be passed round a rotating abrasion mandril of a determined diameter so that the wearing faces of the bar may be ground to the true circle required, it being evident that the greater the number of slots and separate wearing faces in a bar of given length the less will be the grinding necessary to arrive at a true circle.

When a bar in accordance with the invention is to be used in combination with asbestos or other like non-metallic material *g* (Figure 7) the bar may be firmly and securely attached to a piece of asbestos cloth or canvas or other suitable material *h* (Figure 3) by wire staples *i* or otherwise after which it is bent into its V form and is then inserted into the asbestos or other non-metallic material and rubber, the cloth that is attached to the bar being passed round

the outside of the asbestos or like channel, 35 and the whole being then finally vulcanized in a suitable mould under pressure.

Having now described my invention, what I claim as new and desire to secure by Letters Patent is: —

1. Metallic or semi-metallic packing comprising a bar of double wedge shape in section adapted to be folded together to form a V, the double wedge parts being of suitable metal to form the working face while the junction between such parts is formed of a suitable ductile metal embodied in the bar and enabling the parts of the bar to be bent and folded together.

2. Metallic or semi-metallic packing according to claim 1 in which adhesion or amalgamation of the two different metals composing the bar is promoted by treatment of the ductile metal portion.

3. Metallic or semi-metallic packing according to claim 1 in which the ductile portion consists of a plurality of thin sheets superposed one upon another.

4. Metallic or semi-metallic packing according to claim 1 and having transverse 60 slots staggered in relation to one another said slots being cut right through the hard part of the bar and extending a short distance into the soft flexible back portion.

In testimony whereof I have signed my 65 name to this specification.

GEORGE HUNTER ROBINSON.
